UNITED STATES PATENT OFFICE.

WILLIAM E. WOODARD, OF LIMA, OHIO.

LOCOMOTIVE.

1,341,961.

Specification of Letters Patent.

Patented June 1, 1920.

Application filed February 27, 1918. Serial No. 219,350.

To all whom it may concern:

Be it known that I, WILLIAM E. WOODARD, a citizen of the United States, residing at Lima, in the county of Allen and State of Ohio, have invented certain new and useful Improvements in Locomotives, of which the following is a specification.

This invention relates to improvements in locomotives, the purpose being the obtaining of a locomotive engine which will be capable of exerting a relatively high tractive power at low speeds. The invention will be best understood by a statement of the problem presented in securing this result and the methods by which it has been heretofore attempted to accomplish the same.

One of the operating conditions which confronts railway men is to secure sufficient power in locomotives, particularly in freight train movement, not only to move the train over the main line tracks at proper operating speeds, but also to promptly and quickly move heavy trains out of terminals, at sidings, and over controlling grades. Attempts have been made to meet this condition in several different ways, one of which is the use of a Mallet type of locomotive as a simple locomotive. The Mallet locomotive is a compound engine, but it has the capacity of being operated as a simple locomotive, up to speeds of from 6 to 8 miles per hour. Such use of a Mallet locomotive, however, is open to the objection that the operation of the low pressure cylinders as simple engines (by which means the Mallet engine accomplishes the desired result) severely racks the mechanism of such engine and also quickly drains the boiler out of steam; that is to say, as thus operated, the engine is over-cylindered, the capacity of the cylinders being far in excess of the boiler capacity, on which account, such operation of a Mallet locomotive is limited to speeds of from 6 to 8 miles per hour, after which the engine must be operated as a compound locomotive. The reason why such locomotives operating as simple engines quickly overtax the boiler supply is that it is impossible to design such an engine with proper cylinder dimensions to operate both as a compound and as a simple engine.

Another means by which the desired result has been sought is in the use of auxiliary engines under the locomotive tender, such auxiliary engine being connected by flexible

steam-pipe connections to the locomotive. When it is desired to utilize the extra power of the auxiliary unit, the steam is admitted thereto and in this way added power is given to the entire locomotive for the purposes above outlined. This method of operation, however, is open to the objection that it entails a number of complications in design, particularly the complete change in tender construction and the steam-pipe and other connections between the engine and the tender. Moreover, such engines are open to the same objection as operating Mallet locomotives as simple engines, in that the use of the auxiliary engine quickly drains the boiler out of steam. In addition, such engines when not in operation, impose an extra load upon the engine thereby reducing the effective draw bar pull back of the tender.

It is further to be noted that the solution of the difficulty cannot be found in simply extending and enlarging the conventional designs of locomotives into a larger and more powerful machine, as such a procedure does not meet the requirements of the case which are to produce a locomotive coming inside of normal wheel loads and in which the boiler size shall be kept within practical limits and shall be capable of ordinary hand firing. Furthermore, the fact that the end cannot be obtained by merely increasing the size and power of ordinary locomotives will be clear from the following: In a standard locomotive design there is a well-recognized relation between the size of the cylinder, the boiler pressure and the horse-power output of which the engine cylinders are capable. This relation is well defined in the locomotive art so that it may be taken that the maximum cylinder horse-power output for a given cylinder size is a well-established figure. The boiler of the locomotives is proportioned so that it will supply at its maximum output a quantity of steam sufficient to meet the demands of the maximum cylinder horse-power requirements. However, the maximum cylinder horse-power output is not reached until a piston speed of about 1000 to 1200 feet per minute is reached which corresponds with a speed in miles per hour of about 35 to 45 for an ordinary freight locomotive. From this, it is evident that, while the boiler horse-power is available for steam capacity at any and all speeds, the full capacity of the boiler

is not being utilized at speeds lower than that at which the cylinders reach their maximum horse-power output.

From the foregoing, therefore, it will be apparent that the mere magnification of the size and power of standard locomotives will not obtain the desired results. The aim of the present invention is to secure a locomotive which will utilize the full boiler capacity at lower speeds, which means that there will be that much higher tractive power available at the corresponding lower speeds. This may be illustrated by way of comparison with a simple two cylinder locomotive with four pairs of driving wheels and having a maximum boiler capacity of about 2200 horse-power. Such an engine will develop at 35 miles per hour a cylinder horse-power of about 2200, or at that point, the cylinder horse-power requirements will take the full boiler capacity. However, such a locomotive at speeds of 10 miles per hour will exert a maximum tractive power of only about 50,000 pounds and a cylinder horse-power of about 1300. By my improvement, at 35 miles per hour, the cylinders will reach approximately the same cylinder horse-power as the two cylinder engine; namely, 2200, which will, of course, give the same tractive power; but at 10 miles per hour, the improved engine will develop a cylinder horse-power of 1950 with a corresponding tractive power of about 72,000.

In brief, I accomplish the desired ends by providing a locomotive of any predetermined boiler capacity with two or more groups or sets of simple cylinders, the combined normal maximum horse-power output of which is greater than the capacity of the boiler. These groups of cylinders are coupled in any preferred manner to the driving wheels, and they are worked at respective full horse-power effort, up to speeds at which their combined horse-power effort develops to a point approximately equal to the boiler capacity. Thereafter, as the speed increases, I provide means for cutting down or reducing the horse-power effort of the cylinders (which otherwise would increase with the speed and thereby exceed the boiler capacity) and maintain the horse-power effort within the capacity of the boiler, as will hereinafter be pointed out.

In the accompanying drawings, I have illustrated in somewhat diagrammatic form one embodiment or means for accomplishing the desired result.

Of the drawings, Figure 1 is a side elevation of a locomotive embodying my improvements; Fig. 2 is a diagrammatic plan view of a standard form of power means for operating the valve motions adapted to my improvements; Fig. 3 is a plan view of a detail of the power mechanism shown in Fig. 2; Figs. 4 and 5 are respectively a side

and end elevation of a reverse lever having associated therewith a modification of my invention; Fig. 6 is a diagrammatic illustration of a reverse lever mechanism embodying another modification of my invention; Fig. 7 is a diagram illustrating still another form of modification of the application of my invention, Figs. 8 and 9 are diagrammatic views showing different positions of the power means for operating the valve motions to obtain a differential cut off relation; and Fig. 10 is a sectional view of a variable exhaust nozzle suitable for use in connection with my improvements.

Referring now to Fig. 1 it will be seen that I have therein illustrated a locomotive, the boiler A of which has any predetermined horse-power capacity. The locomotive is provided with a forward pair of simple cylinders B and a rear pair C, such cylinders being operatively coupled to any desired number of pairs of driving wheels D, preferably six in number. While the cylinders may be coupled in any desired manner to the driving wheels, I prefer to couple three pairs of drivers to each set of cylinders. Steam is supplied to the forward group in the usual manner through the steam-pipes 7 from each of which a branch 8 leads to the respective cylinder of the rear set. The exhaust from the forward set of cylinders is utilized to create a draft for the fire-box, the exhaust pipe (not shown) being preferably variable, while the rear set of cylinders exhaust to the atmosphere.

The combined normal maximum horse-power output of the two groups of cylinders, *i. e.*, the horse-power developed at piston speeds at which the cylinders are designed to produce maximum horse-power output, is greater than the horse-power capacity of the boiler. I prefer, although it is not necessary, that the two sets of cylinders be designed to have the same normal maximum horse-power output, and I further prefer that at least one of the sets or groups of cylinders be designed to have a normal maximum horse-power output corresponding to the horse-power capacity of the boiler. In this connection I prefer to so design the forward set, for the reason that in the preferred embodiment of my invention, I propose to be using but one set of cylinders when the engine reaches a speed at which normal maximum cylinder horse-power output is obtained, the horse-power output of the other group being reduced to such a point that such group is practically idling. Such being the case, it is more suitable to use the exhaust from the forward group for producing draft in the fire box because of the mechanical difficulties which must be encountered in also using the exhaust from the rear group for this purpose.

As heretofore pointed out, I propose to

utilize the full horse-power output of both groups of cylinders while the engine is running below the speed at which the horse-power output developed by the cylinders is 5 within the capacity of the boiler, and thereafter, I propose to cut down the combined horse-power output of the cylinders so as to keep it within the limits of the boiler capacity. This may be done in any number 10 of ways, the preferred one being, as above indicated, the reduction of the horse-power output of the rear group and the gradual full utilization of the maximum horse-power output of the forward group.

15 As one means for cutting down the horse-power output of the cylinders, I may shift the valve motions so as to alter the relative cut-offs of the two groups of cylinders. In the drawings I have diagrammatically indicated a valve motion D for each group of 20 cylinders. These valve motions are of the standard conventional type known as the Walschert gear, well-known in this art and requiring no statement as to construction or 25 operation. The valve gears are also operated by a standard form of power reverse mechanism E, such, for example, as the well-known Ragonnet power reverse. This power reverse is operatively associated with the 30 reverse lever 9 in the cab in the usual manner. The reach rods 10 and 11, for respectively operating the forward and rear valve motions, are so connected with relation to the power reverse that a differential cut-off between the two valve motions is obtained. 35 To accomplish this I mount on the cross head 12, of the power reverse piston 13, an L-shaped lever member 14, which has one leg pivoted to the cross head as indicated at 40 15. The other leg of said member extends at right angles and has its end engaged in the groove 16 of a cam member 17, supported from the power reverse cylinder. The reach rod 10 is connected to one end of that 45 leg of the member 14 pivoted to the cross head 12, and the reach rod 11 is pivotally connected to the other end of said leg in the manner indicated in Fig. 2. The groove 16 in the cam member 17 is given a reverse 50 or ogee curve. The full forward, midgear and full rear positions of the valve gears are indicated at a, b and c in Fig. 2.

The operation is as follows, assuming that 55 the valve gears are in the midgear position shown: When the reverse lever is moved to full forward position, the member 14 will occupy the same relative position as in Fig. 2; that is to say, the valve motions controlling the steam distribution of the two sets of 60 cylinders will be operated in unison and will cut off at the same proportion of the engine stroke. The forward end of the groove 16, however, is so arranged that the valve motions will operate in unison in this manner 65 until a speed of from 10 to 12 miles per hour

is attained. When, however, the speed is increased and the cut-off of the cylinders is shortened, as in the normal operation of a two cylinder locomotive, the cut-off in the rear group of cylinders is shortened at a greater rate than the cut-off in the forward group, for the reason that as the reverse lever is cut back, the cam member will rock the member 14 about the pivot point 15, thus shortening the cut-off of the rear cylinders 70 much faster than the cut-off of the forward cylinders. This relation between the per cent. of cut-off in the two sets of cylinders is continued through the working range of the cut-offs of both cylinders. Stated in 75 other words, the front pair of cylinders is operated at about the normal cut-off point for an ordinary two cylinder simple operation, whereas, the back pair of cylinders is operated at a considerably shorter cut-off 80 for a speed above 10 to 12 miles per hour. The relation of the cut-off between the two groups of cylinders is determined in the following manner. For any given percentage 85 of cut-off in a steam engine cylinder, there is 90 a corresponding horse-power output, for a given boiler pressure. The cut-offs in the two sets of cylinders, therefore, are so arranged that at any given speed, say for example, 25 miles per hour, the horsepower 95 output of the front group of cylinders plus the horse-power output of the rear group of cylinders is the maximum total which it is possible to supply from the boiler. When the locomotive is operating at high speeds, 100 say for example, 30 to 35 miles per hour, the front group of cylinders is doing practically all the work and the rear group is operating at a cut-off such that it has developed a comparatively low horse-power, 105 practically just enough to move itself. The foregoing will be clear on inspection of Figs. 2, 8 and 9 illustrating various positions of the Ragonnet power reverse and showing the differential effect of the lever 110 member 14 on the valve motions.

This combination of groups of cylinders with variable or differential cut-offs provides the means for utilizing to the fullest possible extent the available horse-power at 115 all speeds without overtaxing the boiler.

The same operation takes place when the engine is run in the reverse direction. It is to be understood that any suitable form of mechanism to secure the desired differential rate of cut-off, between the two groups of cylinders, can be employed, the form in Figs. 2 and 3 being outlined for purposes of illustration only.

I am well aware that it is not new to 125 couple two groups of simple cylinders to sets of driving wheels in one locomotive structure, this being shown, for example, in the patent to Ball and Stafford, No. 1,208,078, the construction of which, however, is 130

subject to the same limitations, which apply in the ordinary two cylinder locomotive arrangement, in that it is necessary to design the boiler large enough to supply the maximum horse-power output of the two groups of cylinders, in order to avoid overtaxing the boiler capacity. The general scheme illustrated in this patent is but one of the ways in which it has been attempted to increase the tractive power of locomotives by increasing the size with the resultant difficulty in wheel loads and size of boiler, etc.

By my improvements, I am enabled to supply, for example, a 0-12-0 type of locomotive having a maximum tractive power of 77,000 pounds with a total weight of only about 330,000 pounds and a wheel load of approximately 55,000 pounds per pair of driving wheels, which would be entirely out of the question if the locomotive were designed with a boiler of sufficient capacity to supply the two groups of cylinders at their full cylinder horse-power, for the provision of such a boiler would involve greatly increased weights with no increase in tractive power at low speeds.

As hereinbefore noted, the exhaust from the front group of cylinders is utilized for producing draft in the smoke box, this being preferable, not only for the reasons already considered, but because, in the preferred manner of cutting down the horse-power effort of the cylinders, the front group is operated at the greater cut-offs, which would increase the volume of exhaust steam. It is also to be noted that because of the fact that it is necessary to use the full boiler capacity at lower speeds than ordinary for an engine of equal boiler horsepower, it will probably be desirable to use some form of variable exhaust to alter the draft conditions, as may be suitable to the running conditions. The form of variable exhaust suitable for this purpose is shown in section in Fig. 10. The construction and operation of this exhaust will be readily understood by those familiar with the art, it being sufficient to point out that the movable head or nozzle 28 is operated from the rod 29, lever 30 and shaft 31 so as to increase or decrease the effective discharge area of the nozzle. It will, of course, be understood that any preferred form of variable exhaust may be employed, the details of the exhaust forming no part of this invention.

In connection with the use of the exhaust of the forward group to produce draft in the smoke box, it may be observed that there is much to be gained in cutting off in the rear group of cylinders at a greater rate than in the front group, instead of at the same rate. If the cut-offs in the groups of cylinders be shortened at the same rate, which, of course, may be done, the front group of cylinders would be discharging

a comparatively small amount of steam through the blast pipe, which would be insufficient to produce the necessary draft upon the fire.

If it is desired to reduce the horse-power output, or rather, maintain the horse-power output within predetermined limits, by shortening the cut-off of both groups of cylinders in unison, the engineman would be required to cut back at a predetermined rate corresponding with the desired maximum horse-power output of the cylinders. In order to determine this rate, a cut-off indicator could be placed in the cab of the locomotive connected to a speed indicator. I have shown such an arrangement in Figs. 4 and 5, in which the reverse lever 9 is carried on a bushing 18 mounted in the quadrant 19. Through this bushing, a shaft 20, of a speed recording instrument 21, extends and is provided with a cut-off indicator arm 22. The speed indicator 21 may be of any standard conventional type, of which there are a number on the market, and it is operated in any of the well-known methods by an operating shaft 23 driven, for example, by a belt connection to an axle. Since the degree of cut-off is determined by the speed, it will be clear that this mechanism provides a simple means for apprising the engineman of the proper notch to which he must cut back.

In Fig. 6 I have shown such a cut-off indicator as has just been described, but in this instance, the indicator arm or pointer 22 is provided with means for releasing the latch 24 of the reverse lever, so that the pointer will shift the reverse lever to the desired notch, if the engineman should be neglectful.

For both the forward and back motion, the pair of indicator arms 22 and 22' can be utilized, such arrangement being shown in diagrammatic form in Fig. 7. By connecting both pointers to a common block 25, slidable in a groove 26, by links 27, the movement of the pointer 22 would be imparted to the pointer 22', in like degree but in reverse direction.

The subject matter relating to the combination of the variable exhaust with a locomotive power unit equipped with more than two cylinders and the subject matter relating to the cut-off indicator mechanism is not here specifically claimed but is claimed in copending applications Serial No. 355,392, filed January 31, 1920, and Serial No. 355,393, also filed January 31, 1920, respectively.

I claim:

1. The combination with a locomotive and two groups of simple cylinders operatively connected to driving wheels, and a valve motion for each group, of mechanism for obtaining a differential cut-off relation between the valve motions to maintain the cyl-

inder horse-power within the capacity of the boiler at all operating speeds.

2. The combination with a locomotive having a boiler of given capacity and two groups of simple cylinders having a normal maximum horse-power output greater than the capacity of the boiler, of a valve motion for each group of cylinders, and a single means for obtaining a differential cut-off between the valve motions to maintain the cylinder horse-power within the capacity of the boiler at all operating speeds.
3. The combination with a locomotive having a boiler of given capacity, of two groups of simple cylinders, the normal maximum horse-power output of which is greater than that of the boiler, a single means for operating one of said groups of cylinders at substantially maximum horse-power output throughout the range of speed, and for operating the second group of cyl-

inders at a less horse-power output, so that the combined horse-power output of both groups shall not substantially exceed the capacity of the boiler.

4. The combination with a locomotive having a boiler, of a plurality of cylinders, the respective horse-power outputs of which are adapted to be relatively varied and a variable exhaust.

5. A locomotive power unit having more than two simple cylinders of a combined normal horse-power capacity greater than the boiler capacity, valve mechanism for said cylinders, and means for unitarily operating said valve mechanism to limit the horse-power output in normal use within the boiler capacity while altering the cut-off to suit varying speeds.

In testimony whereof I have hereunto signed my name.

WILLIAM E. WOODARD.
